UNITED STATES PATENT OFFICE.

MARION KAWA, OF BUFFALO, NEW YORK.

FOLDING RACK FOR DRYING PHOTOGRAPHIC PRINTS.

1,408,604.

Specification of Letters Patent.

Patented Mar. 7, 1922.

Application filed April 24, 1919. Serial No. 292,249.

To all whom it may concern:

Be it known that I, MARION KAWA, a citizen of the United States, residing at Buffalo, in the county of Erie and State of New York, have invented certain new and useful Improvements in Folding Racks for Drying Photographic Prints, of which the following is a specification.

My invention relates to an improved folding rack or stand for drying photographic prints and other similar objects.

One of the objects of my invention is the production of a rack or stand of this type which is simple in construction, durable, easily folded, and as readily extended for use, and in which a number of superposed shelves are provided so that a large capacity is provided for supporting objects.

A further object is the provision of flexible shelves or supports for the prints or other objects, adapted to be normally rolled and retained in such condition upon spring-controlled rollers, and which shelves or supports may be extended and retained in spaced relation one above the other.

With these and other objects in view, the invention consists of a foldable stand or rack having shelves or supports arranged one above another and retained in spaced relation, the whole being collapsible so that it occupies only a small fraction of the space required when extended.

It further consists in a foldable rack or stand having standards normally spaced and retained apart when the rack is extended, and having flexible shelves or supports extending from one standard to the other, with each shelf or support fastened to a spring roller and adapted to be automatically wound around said roller when its free end is released.

It further consists in the novel features of construction and in the arrangement and combination of parts to be hereinafter described and more particularly set forth in the appended claim.

In the drawings:—

Fig. 1 is a perspective view of this improved rack in extended form.

Fig. 2 is a perspective view showing the same folded or collapsed.

Fig. 3 is a broken vertical longitudinal section taken centrally through the rack or stand.

Referring to the parts by reference numerals, 4 designate the standards, each of which comprises two uprights 5 joined together near their upper and lower ends by cross bars 6, 7, respectively. 8 designates a foldable longitudinal connector member comprising two parts 9, 10, these parts being arranged end to end and hinged or pivotally connected together, as at 11, and the outer ends thereof are hinged to the uprights of the standards 4, as at 12. Each part of this connector member comprises two spaced longitudinal bars 13 which are connected at their outer and inner ends by cross bars 14, 15, respectively, the cross bars 15 lying in contact with each other when the rack is extended, as clearly shown in Figs. 1 and 3.

Brace arms 16 are provided which connect each of the side bars of one of the parts of the longitudinal connector member with one of the uprights of each standard 4. These brace arms are formed of two parts pivotally connected together, as at 17, the lower part of each brace arm being pivotally connected to one of the longitudinal bars 13 of each part of the foldable connector member and the upper part to an upright 5 of one of the standards 4. Each brace arm is provided with suitable means to keep the two parts thereof in alinement, in which condition said brace arms are rigid and prevent accidental folding of the rack.

The brace arms are held against folding except in an upward direction, as clearly shown in Fig. 2, and when the braces are extended they hold the two parts of the longitudinal connector member in rigid relation to the standards. In a broad sense, the side bars of the two parts of the longitudinal connector member may be said to form the side bars of the complete connector member since when said parts are swung downwardly into horizontal position, the inner ends of the side bars of the two parts abut, as clearly shown in Fig. 2, making in effect a continuous bar extending from standard to standard.

For convenience in supporting developing trays or other objects, each upright is provided with a swinging shelf 18 pivotally secured to a cross bar 19, as at 20, each of said cross bars extending from upright to upright of one of the standards and connect-

ing said uprights together, said swinging shelves are held in horizontal position by folding braces 27, one end of each brace being pivotally secured to one of the shelves 5 and the other end to one of the uprights 5. When folding the brace the shelves 18 may be lowered to the position shown in Fig. 2. 21 designate flexible shelves or supports on which the prints or other light-weight 10 articles may be placed. These shelves are arranged one above another, and are preferably formed of rubber cloth or other suitable material, one end of each shelf being secured to a spring controlled roller 22 15 similar to the ordinary spring roller used on window shades, said rollers being positioned between the uprights 5 of one standard and having opposite ends journaled in said uprights in any approved manner. These 20 rollers are so arranged that the flexible material forming the shelves is normally wound around the rollers and retained in such condition by the springs of the spring roller, in the same manner as a window shade is 25 retained in rolled up condition on its spring roller, and when these shelves are extended so as to reach from one standard to the other, as shown in Figs. 1 and 3, the springs of the rollers become wound up or strained, 30 and the free ends of the shelves are hooked or otherwise secured to the uprights 5 of the opposite standards, as at 23.

By reason of the springs of the rollers 22 being strained or wound up, the shelves, 35 when their free ends are attached to the opposite standards, are retained in taut condition so as to properly support light-weight articles, particularly prints or similar objects to be dried.

40 When it is desired to fold the rack, the free ends of the shelves 21 are disconnected from the uprights of the standard to which they are attached and the springs of the rollers 22 immediately act to wind up or roll 45 the flexible shelves around said rollers, whereupon the shelves assume the condition shown in Fig. 2. The brace arms 16 may then be folded, after which the two parts of the connector member 8 may be folded upon 50 themselves and swung upwardly on the pivots 12 by means of which the outer ends of said two parts are connected to the standards. When thus manipulating the device, the two standards are moved toward each 55 other and assume the position shown in Fig. 2, with the folded connector member in

parallel position, or substantially so, between the two standards.

While the folding of the rack may be accomplished in the manner described, it 60 possesses the advantages of being folded without detaching any of the parts, such as for instance, detaching the free ends of the shelves 21 from the uprights of the standards to which they are connected, as 65 the spring-controlled rollers around which said shelves are secured will automatically cause the shelves to be rolled up when folding the rack. If, for instance, any of the lower shelves are in use, the hinged connector member may fold upwardly between the standards when moving said standards toward each other, and the shelves will simply yield to assume substantially the 70 outline of the folded connector member. The 75 two uppermost shelves, however, will continue to assume a perfectly horizontal position although shortened by reason of the major portion having been rolled around the rollers to which they are secured. It is 80 apparent therefore that the shelves will automatically roll up or will be capable of being flexed upwardly and at the same time be shortened by reason of portions thereof being rolled around their rollers. 85

In order to retain the rack in folded position, a chain 24 may be attached with one end to one of the standards. This chain has a hook or other securing device 25 at its opposite end which is to be entered into an 90 eye 26, or any similar retainer device may be used for this purpose.

Having thus described my invention, what I claim is:—

A rack of the kind described, comprising 95 two standards, a folding connector-member having two parts pivotally connected at their outer ends to said standards and pivotally connected together at their inner ends, folding braces connecting each part of said connector-member with one of said standards, spring-wound flexible elements arranged one above another and secured to one of said standards and extending to the other standard for connection thereto, said flexible elements being adapted to be rolled up automatically when disengaged from said last-mentioned standard and said connector-member is folded. 100 105

110 In testimony whereof I affix my signature.

MARION KAWA.
